UNITED STATES PATENT OFFICE.

OLIVER D. CURRIER, OF CROWN POINT, NEW YORK.

SANITARY SEAT-COVER.

1,254,029.

Specification of Letters Patent. Patented Jan. 22, 1918.

Application filed March 1, 1917. Serial No. 151,837.

To all whom it may concern:

Be it known that I, OLIVER D. CURRIER, a citizen of the United States, and resident of Crown Point, in the county of Essex and 5 State of New York, have invented certain new and useful Improvements in Sanitary Seat-Covers, of which the following is a specification.

The invention relates to sanitary applications for toilet seats.

The dominant object of the invention is to provide a sanitary-cover for toilet seats, particularly adapted for use in public stations, whereby, the seat may be readily covered with the same, thus, protecting the user, and further, may be also removed therefrom and destroyed.

Another object of the invention is to provide novel means for retaining and feeding 20 the sanitary covers, the same being in the form of a roll and being adapted to be fed through guide means over the seats.

A further object of the invention is to provide a device of the character mentioned 25 which, may be applied to the usual toilet without alteration thereto and when applied, will not in any way, interfere with the operation of the same.

All of the foregoing together with additional advantageous details and arrangements of parts of the preferred embodiment 30 of my invention will be clear from the specific description hereinafter contained, when read in connection with the accompanying 35 drawings forming a part thereof, wherein said embodiment of the invention is illustrated for the purpose of facilitating a full understanding of the present improvements.

In the drawings:

40 Figure 1 is a side elevation of the usual toilet with my improved cover applied thereto;

Fig. 2 is a top plan of the same;

Fig. 3 is a top plan of the toilet seat with 45 the cover removed;

Fig. 4 is a detail in perspective of one of the cover guiding elements; and

Fig. 5 is a similar view of a second guiding element.

50 Similar characters of reference are employed in all of the above described views to indicate corresponding parts.

Referring more specifically to the several figures of the said drawings, it is to be noted 55 that I have shown by way of illustration my improved sanitary cover and support there-

for as applied to the conventional type of toilet and toilet seats, indicated by the numerals, 1 and 2, respectively. The usual hinged closure 3 is secured to the rear extremity of the seat 2 as at 4 and has arranged upon the opposite side portions thereof a plurality of substantially arcuate shaped bracket arms 5, the same being secured to the said closure through the medium of a plurality of fastening devices 6. Offset bearing pintles are formed upon the upper extremities of the bracket arms 5 and rotatably supported thereon is a roll 7 composed of the sanitary paper covers which are 70 to be drawn over the seat 2.

The covers, designated 8 are formed of a continuous sheet of paper or other suitable material and are adapted to permit the user to tear one of the same from the sheet when 75 desired. Substantially diamond shaped openings 9 are formed within each of the covers 8 and by reason of their peculiar shape may be readily passed under the sheet guide elements which will be subsequently 80 described.

As a means for feeding the covers 8 downwardly from the roll 7 over the seat 2, there is secured to the rear portion of the same a transversely disposed arm 10, one extremity of which is bent upon itself as at 11 and is secured to the adjacent portion of the seat by rivets or other like devices as at 12. It is to be noted, that the portion of the arm 11 that is bent upon itself and secured 90 to the seat 2 is slightly spaced from the body portion thereof, consequently, providing a way of sufficient size to admit the covers 8 therethrough.

To the forward portion of the seat 2 there 95 is secured a second guide element 13, the rear portion of which is reduced and is secured to the under surface of the seat by passing suitable fastening devices 14 through the same into engagement with the 100 said seat. It is to be noted, that the free or forward extremity of the guide element 13 is curved upwardly and is provided with a transversely disposed elongated slot or way 15, the way being of a size to permit snug 105 passage of the various covers 8 therethrough. That portion of the guide element 13 in which the way 15 is formed may be and preferably is so curved as to provide a substantially convexed lip 16, whereby the 110 paper cover may be readily drawn through the way formed therein. Obviously, by pro-

viding the guides 10 and 13, proper positioning of the various paper covers 8 over the seat 2 is insured.

By arranging the roll 7 upon the bracket arms 5 secured to the closure 3, the device is rendered compact and does not require alteration to the usual construction of the toilet. Further, moving of the closure 3 to position over the seat 2 is permitted, since, 10 the mounting of the cover roll 7 upon the same is such as to allow free and uninterrupted movement thereof.

In operation, the free extremity of the outermost cover 8 is grasped by the user and 15 drawn between the several guides 10 and 13 to a position over the seat 2. As it becomes necessary to renew the roll 7, the upper extremities of the bracket arms 5 may be flexed outwardly for a distance sufficient to permit 20 the arranging of a new roll therebetween, whereupon the offset bearing pintle of the same may be engaged with the bearing opening formed therein.

While I have herein disclosed a specific 25 embodiment of the invention, it will be apparent to persons skilled in the art that the invention is capable of embodiment in other forms and devices differing in detail and arrangement from that shown, as may be in 30 keeping with the hereto appended claims.

I claim:

1. A device of the character described, including paper roll supporting means, a 35 guide arm having one end of the same bent upon itself and secured to the rear portion

of a toilet seat, and a second guide element secured to the forward portion of the toilet seat, as and for the purpose set forth.

2. A device of the character described, including paper roll supporting means, a 40 guide arm having one end of the same bent upon itself and offset and secured to the rear portion of the seat, a second guide element secured to the forward portion of the seat and being offset intermediate its length and 45 having an elongated way formed in the free extremity thereof, as and for the purpose set forth.

3. A device of the character described including, in combination with the hinged 50 closure of a toilet seat, paper roll supporting means secured to said closure, a guide arm having one end of the same bent upon itself and secured to the rear portion of the seat, a second guide element having an elongated way formed in the free extremity 55 thereof secured to the forward portion of the seat, as and for the purpose set forth.

4. The combination with a toilet seat, and a hingedly connected cover therefor, of a 60 plurality of arcuately shaped brackets secured to the cover, paper guiding means mounted on the front and rear portions of the seat, and a roll of paper mounted on the brackets, the paper being adapted to be 65 trained along the cover and through the guiding means.

In testimony whereof, I affix my signature hereto.

OLIVER D. CURRIER.
